UNITED STATES PATENT OFFICE.

FELIX EMILE VALOIS, OF HAVERHILL, MASSACHUSETTS, ASSIGNOR TO HAMEL SHOE MACHINERY COMPANY, OF LYNN, MASSACHUSETTS, A CORPORATION OF MASSACHUSETTS.

SHUTTLE MECHANISM.

1,418,752.

Specification of Letters Patent. Patented June 6, 1922.

Application filed August 1, 1918. Serial No. 247,751.

To all whom it may concern:

Be it known that I, FELIX EMILE VALOIS, a citizen of the United States, residing at Haverhill, county of Essex, State of Massachusetts, have invented a certain new and useful Improvement in Shuttle Mechanism, of which the following is a specification, reference being had therein to the accompanying drawings.

10 My invention has for its object an improvement in sewing machines for use in the manufacture of boots and shoes and particularly a machine known as an outsole or rapid stitcher, such a machine being provided with 15 two threads one of which is supplied from a bobbin located in a shuttle. In machines of this character considerable difficulty has heretofore been experienced in sewing around the shank of so-called deep shank 20 shoes, that is, shoes in which the sole of the shoe at the heel is much higher than the sole of the shoe at the toe. The so-called Louis Shoe is an illustration of a deep shank shoe. In the manufacture of such shoes it has been 25 found very difficult to sew the shank and particularly sew the shank rapidly and neatly because when the shank is reached the shoe has to be tilted into a position in which the ball of the shoe strikes the shuttle case 30 preventing further movement of the shoe to bring the edge of the sole at the shank into proper position with relation to the stitch forming and work feeding instrumentalities. Furthermore, when operating on this portion 35 of shoes of this character the operator finds difficulty owing to the fact that the shuttle case cuts off his view of the shoe at a point where the stitch forming instrumentalities are operating on the edge of the sole. 40 I obviate the difficulties mentioned by placing the shuttle with its front face on an angle oblique to the line of feed of the shoe and by providing suitable mechanism for operating the shuttle in this oblique position. 45 When the shuttle is placed in this manner the shoe may be passed through the stitch forming instrumentalities always maintaining 50 the edge of the sole at the stitching point in proper relation to the stitch forming instrumentalities without striking the shuttle case. The view of the operator is not obstructed and it results that the operator may work much more rapidly when sewing

around the shank of the shoe and may produce more perfect work at greater speed.

Furthermore, perfect work may be produced because the sole will not be marred by striking the shuttle case. In the following description I have referred only to the shuttle and mechanism for operating it and to the essential elements of the stitch forming mechanism. The other parts of the sewing machine do not have to do with my present invention and, therefore, have not been described in detail.

65 The invention will be fully understood from the following description when taken in connection with the accompanying drawings and the novel features thereof will be pointed out and clearly defined in the claims 70 at the close of this specification.

In the drawings, Fig. 1 is a front elevation of a part of a sewing machine embodying my invention.

Fig. 2 is a top plan view of the parts 75 shown in Fig. 1.

Referring now to the drawings, at A is shown the outline of a shoe of the deep shank variety, said shoe being in one position which it occupies during the stitching 80 operation. At 11 is shown the frame of the machine. The needle which is of the ordinary curved barbed variety is shown at 12, the looper at 13, the table at 14 and the awl at 15. The machine is provided with the 85 other usual stitch forming instrumentalities but it is not necessary to refer to them in detail. The machine is of the awl feed type the work being fed by the awl 15 in the direction of the arrow in Fig. 2. At 5 is 90 shown the front feed or front thread delivery shuttle carried in a shuttle case 16 and driven by a shuttle driver of usual form mounted on a shuttle shaft 17, which is placed at the rear face of the shuttle and is 95 disposed at an angle to the line of feed and to the axis about which the needle oscillates. The front face of the shuttle, that is, the face indicated by the line designated 18 in Fig. 2 is set at an oblique angle to the line of 100 feed of the work as indicated by the arrow in Fig. 2 and in a plane substantially coincident with the stitching point. This angle is about 35° but may be made more or less according to the character of the work which 105 the machine is intended to do. I find, how-

ever, that the angle indicated is a satisfactory one for most classes of work. This angle should not be too large, however, or a shuttle having the thread drawn from the 5 front cannot be used satisfactorily. Should too large an angle be used with such a shuttle, it must be so positioned, in order to clear the needle, that the thread leaves the bobbin considerably to one side of the needle 10 plane and contacts with the moving shuttle or with the machine parts on its passage to the work. As the shuttle moves, such action would remove the wax from the thread gumming up the moving parts and interfering 15 materially with their proper operation and also modifying the tension of the bobbin thread, thus interfering with proper stitching.

In order to avoid this defect in the stitching, a shuttle having the thread drawn from the back or needle side might be used; but these shuttles have the great disadvantage of rendering the bobbin very inaccessible for thread replenishment or otherwise, and in 20 a wax thread machine where these parts are heated this is a very serious drawback. By arranging the shuttle as described, I am able to use a front feed shuttle, retaining the ready accessibility of the bobbin possible 25 with this type, and avoiding the necessity of tipping the shoe while sewing around the shank, but at the same time retaining the bobbin thread clear of the shuttle and other parts. This can be done satisfactorily up 30 to angles not much exceeding 45 degrees, and with shuttles as ordinarily constructed a somewhat less angle is usually necessary or at least more satisfactory. On the shuttle shaft 17 is a gear 19 meshing with a 35 gear 20 on the driving shaft 21 which is itself driven by a bevel gear 22 meshing with a bevel gear 23 on the main shaft 24 of the machine. The gears 19 and 20 may be of any suitable form to transmit the motion 40 from the shaft 21 to the shaft 17, said shafts being set at an angle one to the other. In practice I make the gear 19 a bevel gear and the gear 20 a spiral bevel gear. The ratio of the gear 20 to the gear 45 19 is three to two and that of the gear 23 to the gear 22 is two to one so that the ratio of the shaft 24 to that of the shuttle shaft 50 17 is one to three.

From Fig. 1 it will be seen that when 55 the stitch forming instrumentalities are working along the heel and shank of the shoe, the ball of the shoe is nearly on a level with the centre of the shuttle. From Fig. 2 it will be seen that the shuttle being placed 60 in a substantially vertical plane at an angle as shown, the shoe does not strike the shuttle case and the face of the welt at the point where the stitching is taking place may lie flat on the table. More perfect and stronger 65 stitching with less manual effort on the part

of the operator is produced, particularly as the locks of the stitches are not displaced as is the case if the face of the welt does not lie flat on the table.

The line of vision of the operator when 70 sewing the shoe is downward along an oblique line which is nearly vertical. When the shuttle is in the position shown, this line of vision is unobstructed. This enables the operator to hold his head in a natural position and at the same time watch the work 75 perfectly.

What I claim is:

1. In an out-sole stitcher, in combination, a work-support having a work-engaging surface which is substantially parallel to the general plane of the shoe-sole at the stitching point, a curved hooked needle and needle-carrier journaled to oscillate about an axis disposed in a plane substantially coincident 80 with the plane of the shoe-sole at the stitching point but beyond the edge of the shoe-sole remote from the operator, feeding mechanism, a front-thread-delivery shuttle having its front-face arranged at an acute angle 85 to the line of feed, and means at the rear of the shuttle for driving the latter.

2. In an out-sole stitcher, in combination, a work-support having a work-engaging surface which is substantially parallel to the 90 general plane of the shoe-sole at the stitching point, a curved hooked needle and needle-carrier journaled to oscillate about an axis disposed in a plane substantially coincident with the plane of the shoe-sole at the stitching point but beyond the edge of the shoe-sole remote from the operator, feeding mechanism, a front-thread-delivery shuttle having its front face arranged at an acute angle 95 to the line of feed, and in a plane substantially coincident with the stitching point, and means at the rear of the shuttle for driving the latter.

3. In an out-sole stitcher, in combination, a work-support having a work-engaging surface which is substantially parallel to the general plane of the shoe-sole at the stitching point, a curved hooked needle and needle-carrier journaled to oscillate about an axis disposed in a plane substantially coincident 110 with the plane of the shoe-sole at the stitching point but beyond the edge of the shoe-sole remote from the operator, feeding mechanism, a front-thread-delivery shuttle having its front-face arranged at an acute angle 115 to the line of feed, said shuttle being so set relative to the stitching point that the path of the ascending shuttle beak is substantially coincident with a line passing through the stitching point and perpendicular to the 120 plane of the work-support, whereby the loop drawn out by the shuttle will be substantially normal to the work.

4. In an out-sole stitcher, in combination, a work-support having a work-engaging sur- 130

face which is substantially parallel to the general plane of the shoe-sole at the stitching point, a curved hooked needle and needle-carrier journaled to oscillate about an axis disposed in a plane substantially coincident with the plane of the shoe-sole at the stitching point but beyond the edge of the shoe-sole remote from the operator, feeding mech-

anism, a front-thread-delivery shuttle having its front face arranged at an acute angle 10 to the line of feed, and a shuttle driving shaft arranged at the rear face of the shuttle and inclined to the axis of oscillation of the needle.

In testimony whereof I affix my signature.

FELIX EMILE VALOIS.
